FLYING SHEAR

Florence C. Biggert, Jr., Crafton, Pa., assignor to
United Engineering & Foundry Company, Pittsburgh, Pa., a corporation of Pennsylvania

Application June 17, 1933, Serial No. 676,313

45 Claims. (Cl. 164—68)

This invention relates to what is known in the metal rolling art as a flying shear, and more particularly to a shear of the rotary type adapted for cutting metal strips, bars, billets, and elongate products of that nature, into sections of predetermined lengths while in motion.

The primary object of the invention generally stated is to provide an improved shear of this character which is capable of being adjusted to produce with a very high degree of accuracy cuts of any desired length within a relatively wide range of lengths.

Another object is to provide a rotary type shear in which the shear blades are at all times driven at a peripheral speed corresponding within tolerable cutting limits with the lineal speed of the stock being operated upon, and in which adjustments can be made to produce cuts of different lengths without altering to any substantial extent the speed of the shear.

A further object is to provide in a shear of this nature for easily and quickly, as well as accurately, adjusting it to produce cuts of different preselected lengths and for doing so while it is in motion as well as when it is idle.

It is also an object to provide for controlling the shear to automatically crop the leading end of each piece of stock fed into it, and for doing so accurately and without interrupting or altering the normal rotary movement of the cutting elements, except to move them into cutting opposition with each other at the proper instant.

A more specific object is to provide a flying shear of the rotary type in which a plurality of cutting blades is provided on each of the blade carriers and in which provision is made for moving such carriers into and out of cutting opposition with each other in such a manner as to selectively utilize the various blades mounted thereon for producing cuts of various lengths, and for doing so at relatively high speeds without marring or marking of the stock between cuts, or without interfering with the rotary movement of the carriers, or causing them to lose any of their momentum either during the period of cutting or between cuts.

These and numerous other objects, as well as the various other novel features and advantages of the invention, will be apparent when the following detailed description is read in conjunction with the accompanying drawings, in which Fig. 1 is a plan view of a shear constructed in accordance with the invention; Fig. 2 a front elevational view of the same shear; Fig. 3 a vertical section taken on the line III—III of Fig. 1; Fig. 4 a

vertical section taken on the line IV—IV of Fig. 1, showing the blade carriers in position to produce a cut; Fig. 5 a view similar to Fig. 4, showing the blade carriers in a separated or inoperative position and illustrating the mechanism for shifting the carriers somewhat schematically; Fig. 6 a horizontal section taken through the center of the Geneva and pin wheels employed for operating the blade-carrier adjusting mechanism; Fig. 7 a somewhat schematic view shown partly in section and partly in elevation of the control mechanism utilized to control the operation of the blade-carrier adjusting cams and including a wiring diagram of the electrical control mechanism utilized therewith; Fig. 8 a plan view to enlarged scale of one of the pin-selecting units of the control mechanism shown in Fig. 7; Fig. 9 a sectional view taken on the line IX—IX of Fig. 8; Fig. 10 a sectional view taken on the line X—X of Fig. 8; Fig. 11 a sectional view taken on the line XI—XI of Fig. 8; Fig. 12 a sectional view taken on the line XII—XII of Fig. 8; and Fig. 13 a fragmentary vertical section taken on the line XIII—XIII of Fig. 2.

Referring in detail to the embodiment of the invention shown in the drawings, and first more particularly to Figs. 1 to 5, inclusive, the numeral 1 designates the supporting frame of the shear which is made up principally of a pair of end uprights or bearing housings 2 and 3 which are mounted on a base 4 and have their upper ends firmly joined together by a cover section or crossbeam 5. Between such uprights there is arranged a pair of cooperating rotary blade carriers 6 and 7, on each of which three axially disposed cutting blades 8a, 8b and 8c, and 9a, 9b and 9c, respectively, spaced 120° apart are mounted.

The ends or axes 11 and 12 of these carriers are mounted in suitable bearings 13 and 14 which are supported in windows 15 and 16 provided in the uprights 2 and 3 for their reception. In accordance with this embodiment of the invention, the upper carrier 6 is held against other than rotary movement by bolts 17 and 18 which secure the upper bearings 13 rigidly to the crosspiece 5 at the top of the frame 1. The lower carrier, however, is mounted for vertical reciprocation so that it may be moved into and out of cutting opposition with the upper carrier to vary the lengths of the cuts which the shear will produce, as will presently appear.

For supporting the bearings 14 in which the lower carrier 7 is mounted and for controlling the vertical reciprocation of such carrier, a pair of cam wheels 21 is mounted on a shaft 22 supported

in suitable bearings 23 located directly below the lower ends of the bearings 14. On each of these cams there is provided a series of six identically disposed and uniformly spaced lobes 24 which are 5 adapted to lift the bearings 14 and the lower carrier 7 into cutting position as the shaft 22 is rotated, each time their apices are moved under the bearings 14, and they are so shaped as to provide both smooth and rapid movement of the 10 lower carrier.

To facilitate the movement of the cams 21 under the lower ends of the bearings 14, the latter are equipped with rollers 25 which are arranged to ride upon the periphery of the cams, 15 and to insure the lower blade carrier 7 following the cams as it is rotated when the shear 13 operated at relatively high speeds, a pair of coil springs 28 having sufficient strength for such purpose is positioned between the lower faces of 20 the upper bearings 13 and the upper faces of the lower bearings 14.

For operating the shear a motor 31 is coupled to it through a gear change unit 32, which latter is employed to vary the speed of the shear with 25 respect to the stock for a purpose which will presently appear. Although various forms of speed changing devices may be used in this capacity, a gear unit such as that disclosed in United States Patent No. 1,852,282, granted to 30 the present inventor April 5, 1932, is recommended because of the fine speed adjustments which such a unit may be made to produce. To operate the shear in synchronism with stock, which is necessary for the production of cuts of accurate 35 length, a drive 10 for the stock-feeding means, not shown, may be connected directly to the drive shaft of the shear motor 31, or, in the event the shear is operated to handle stock delivered directly from a mill, a synchronous type motor 31 40 may be employed, and connected to receive its operating current from a synchronous generator operated by the mill.

As illustrated in the drawings, a pinion 34 is provided on the driven shaft 33 of the gear unit 45 32 and arranged to mesh with a gear 35 mounted on a shaft 36 which is rigidly connected through suitable couplings 37 with the axis 11 of the upper blade carrier 6. For driving the lower blade carrier 7 in synchronism with the upper 50 55 and at the same time permit it to be adjusted vertically in its supports, a gear 38 is mounted on the shaft 36 of the upper carrier 6 and meshed with a gear 39 of similar size mounted on a shaft 41 that in turn is connected by means of shaft 40 45 and a pair of flexible couplings 42 to the axis 12 of the lower carrier 7.

For preventing the blades on the two carriers from jamming or separating to any deleterious extent when a cut is being made, gears 43 and 44 60 are provided on the opposite ends of the axes 11 and 12 of the two carriers and arranged to mesh and hold the carriers in accurate alignment whenever the lower carrier is moved into cutting opposition with the upper carrier. The teeth of 65 these gears are so shaped that they will both readily mesh with each other when they are moved together and positively insure the proper alignment of the cutting blades, it being appreciated that, as the two drive shafts on which the carriers are mounted are positively tied together, the gears 43 and 44 are at all times in proper alignment for meshing.

For driving the shaft 22 on which the lower blade-carrier adjusting cams 21 are mounted, a 70 miter gear 45 is also provided on the driven shaft

33 of the gear change unit 32 and arranged to mesh with a similar gear 46 mounted on the end of a shaft 47 which is supported at its lower end in a suitable bearing 48 provided at the base of the shear. Adjacent the lower end of this shaft a miter gear 49 is keyed, and is meshed with a similar gear 51 mounted on a shaft 52 which is suitably supported in parallel alignment with the cam shaft 22. On the end of this latter shaft adjacent the shear frame there is provided a 10 pinion 53 which is arranged to mesh with a gear 50 comprising the outer rim of a pin wheel 54 mounted on a shaft 55 disposed in parallel relation between it and the center line of the cam shaft 22 upon which the cam wheels 21 are 15 mounted.

The pin wheel 54, just referred to, is employed to operate a wheel 64 in the nature of a Geneva wheel and hereinafter referred to as such which is mounted on the adjacent end of the cam shaft 20 22, being equipped, as shown best in Figs. 5 and 8, with twelve evenly spaced pins 56a, 56b, 56c, 56d, 56e, 56f, 56g, 56h, 56i, 56j, 56k and 56l, which are arranged to be engaged in the slots 65 of the Geneva wheel. For effecting such engagement 25 these pins are mounted for axial movement in a circular series of openings 57a, 57b, 57c, 57d, 57e, 57f, 57g, 57h, 57i, 57j, 57k and 57l, respectively, provided in the web of the wheel, and for guiding them in such movement their outer ends are 30 extended, respectively, through a series of holes 58a, 58b, 58c, 58d, 58e, 58f, 58g, 58h, 58i, 58k and 58l provided in a guide wheel 59 mounted on the pin wheel supporting shaft 55 in spaced relation with the pin wheel. Between the outer face 35 of this guide wheel 59 and a fitting 61 secured to the outer end of each of the pins 56a to 56l by an extension 62, a compression spring 63 is mounted, which is adapted to normally hold the pins in an 40 inoperative position.

The Geneva wheel 64 is provided with the same number of radial slots 65 as there are lobes 24 on the cam wheels 21, and these are spaced midway between such lobes so as to place them in a position to receive the pins 56a to 56l when the lower 45 carrier 7 is at the lower end of its stroke, which it is when the rollers 25 on the lower ends of the lower bearings 14 rest in the valleys between the lobes 24, as they normally do. The depth of these slots 65, and the design and arrangement 50 of the pin wheel 54 and the Geneva wheel 64, are made such that when one of the pins 56a to 56l on the pin wheel 54 is operated to engage one of the slots 65 it will cause the Geneva wheel to turn a distance equal to the length of one of the cam 55 lobes 24, i. e., 60°, before it passes out of such slot. To produce such a turning of the Geneva wheel a pin wheel is required which will turn 120° during the period the pin is engaged in the Geneva wheel.

As set forth above, the pin wheel 54 is driven in positive synchronism with the blade carriers 6 and 7, and the pins 56 are so timed with respect to the blades 8 and 9 that a pair of blades is in cutting opposition to each other at the instant 65 each pin arrives at the edge of the Geneva wheel. Consequently, as the Geneva wheel when idle is always in a position to be engaged by the pins, it may be set in motion by any one of the pins so long as the pin selected for such purpose is 70 operated to engage such wheel before it reaches its edge.

In the particular machine illustrated, to provide a smooth cam action, as well as a smooth movement of the lower carrier at both high and low 75

speeds, the pin wheel is driven at one-fourth the speed of the blade carriers. In other words the blade carriers are made to make one and one-third revolutions while the pin wheel is rotating one-third of a revolution, which is the distance the latter travels while the pins are engaged in the Geneva wheel. For example, when a pin such as pin 56a, Fig. 5, enters a slot 65 in the Geneva wheel, a pair of blades 8b and 9b will be in cutting opposition to each other. At the same instant the bearing rollers 25 will be at the points o on the cam wheels 21. During the first 30° travel of the pin wheel after the pin 56a engages the Geneva wheel, it will move to the point m , while the lobe on the cam will be moved to the point o^1 which is less than 15° . During such period the next pair of blades 8c and 9c will move into cutting opposition. The amount which the carrier 7 will be moved vertically, due to the movement of the cams 21, as indicated, will be less than half of its vertical movement.

With the next 30° travel of the pin wheel, the pin 56a is moved to the point m^1 , the blades 8a and 9a into cutting opposition, and the cams 21 to the point o^{11} , at which time the lower carrier 7 is in cutting position. As will be appreciated, during this period the Geneva wheel is moved an angular distance in excess of 15° and the lower carrier the greater portion of its upward travel. During the following 30° travel of the pin wheel, the succeeding set of blades 8b and 9b moves into cutting opposition, and the carrier is lowered the amount it is raised the preceding period, the cam moving to the point o^{111} and the pin to the point m^{11} . Hence, the blades moving into cutting opposition just before and just after each cut are prevented from engaging the stock, which normally passes between the carriers at an elevation well out of the path of the blades on both carriers. During the last 30° travel of the pin 56a in the Geneva wheel, the cam lobe 24 is moved to the point o^1 where it remains until another pin is engaged in the Geneva wheel.

With such an arrangement, as the pin wheel 54 has to travel 120° for each pin 56 to clear the Geneva wheel, only every fourth pin may be engaged on the Geneva wheel, and the shortest lengths which may be cut without altering the speed of the carriers with respect to the speed of the stock, is one which is equal to a span of four cutting blades, or to one and one-third revolutions of the carriers. This, of course, may be reduced by one-half by reducing the ratio of the pin wheel drive to two to one, or increased by stepping it up to a higher ratio.

Cuts having a length in excess of the aforementioned minimum length may be produced by merely controlling the selection of the pins 56 made to enter the Geneva wheel. For example, every fifth pin will produce a cut equal to one and two-thirds revolutions of the carriers, every sixth pin one equal to every two revolutions of the carriers, and so on. To produce cuts between these steps the gear change unit 32 may be brought into play to vary the speed of the shear with respect to the speed of the stock, and as the distance between the blades is small due to the plurality of blades used, any length of cut desired may be produced without changing the rotary speed of the shear with respect to that of the stock sufficiently to deleteriously interfere with the operation of the shear. These adjustments, however, should be such that the speed of the shear is increased over that of the strip so that there

will be no possibility of the shear causing the stock to buckle when a cut is made.

To assist in preventing the blades on the two carriers from marking or otherwise damaging the stock between cuts, an apron 60 may be mounted between the uprights 2 and 3 in front of the blade carriers to guide the stock through the shear. Such an apron, as shown in Fig. 13, is pivotally mounted on a shaft 60d secured to the uprights 2 and 3 and fulcrumed on a pair of cams 60a mounted on the opposite ends of a shaft 60b also supported in the two uprights 2 and 3 between the outer shaft 60d and the blade carriers. For operating such cams a tailpiece 60c is provided on each cam 60a and is arranged to be engaged at the free end thereof by bosses 14a formed on the adjacent faces of the bearings 14 of the lower blade carrier 7. Thus the cams 60a are caused to oscillate each time the lower carrier is raised and lowered, and to function as intended the faces 60e of the cams are so made that they cause the apron to maintain the stock at all times, except when a cut is made, sufficiently above the lower carrier to prevent the blades on such carrier from striking it, but not high enough at any time for it to be struck by the upper blades.

To facilitate the movement of the pins 56 in the slots 65 of the Geneva wheel, a roller 66 is mounted preferably in roller bearings on the lower end of each pin and provided with a diameter which is but slightly less than the width of the slots 65, and to avoid any possible jamming of the pins 56 with the Geneva wheel in the event any of the pins attempts to engage such wheel when its slots are not in the proper position for their reception, the outer edge, or the periphery 70, of the Geneva wheel is tapered away from the pin wheels so that the pins will ride upon the surface of the inclined portion 70 and into the first available slot, or over the surface of the Geneva wheel without causing any damage. It will be appreciated of course that the Geneva wheel is normally held in proper position for receiving the pins 56 when the Geneva wheel is idle by the engagement of the lower blade carrier bearing 14 in the valleys of the cam wheels 21.

For operating the pins 56 in the pin wheel 54 an electromagnet 67 of suitable construction is mounted on the pin wheel about each pin. As shown in Fig. 6, these magnets each comprise a coil 67z which is secured to the web of the wheel 54, and cooperating with each is a disc of permeable material 67y, which is mounted on the pin above the coil and adapted to function both as an armature for moving and as a stop for limiting the movement of the pin. To increase the efficiency of the magnet it may be spaced from the wheel 54, if such is made of permeable material, by a spacer 67x made of non-permeable material, or material having a very low permeability as may be the pin itself.

In order to connect the different pin magnets to a source of current supply, such as line conductors L_1 and L_2 , (Fig. 7) so that they may be operated independently of each other, a series of slip rings 69, 69a, 69b, 69c, 69d, 69e, 69f, 69g, 69h, 69i, 69j, 69k and 69l is provided on the pin wheel supporting shaft 55 being mounted in insulated relation to each other, see Fig. 7. Of these, one ring 69 is connected in common to one end of all of the magnet coils 67z by a common conductor 71, while the others are connected by individual conductors 71a to 71l to the other ends of such coils. By a suitable brush and conductor 72, the slip ring 69 connected in common to all

of the coils 67₂ is connected to line conductor L₁. In a like fashion the remaining slip rings 69_a to 69₇ are connected by separate conductors 72_a to 72₇, inclusive, to line conductor L₂ through a series of relays 74_a to 74₇ which are employed to control the energization of the pin magnets, being provided with normally open bridging members 75_a to 75₇ which are connected directly in such conductors.

10 In order to automatically and selectively control the operation of the pins 56_a to 56₇ in the pin wheel 54, a series of twelve insulated collector rings 77_a to 77₇ is provided on an extension 76 of the pin wheel shaft 55. To these rings one end of the actuating coils 83_a to 83₇ of the relays 74_a to 74₇, respectively, is connected by a series of conductors 84_a to 84₇. The other ends of such coils are in turn connected by a series of conductors 82_a to 82₇, respectively, to a series of interrupted conductor bands 79_a to 79₇, respectively, provided on a drum switch 78 which is mounted on the opposite end of the extension 76 of the pin wheel shaft 55. These latter bands, as shown, are in turn all connected to each other and to an extension M₁ of line conductor L₁ by a conductor 81.

To complete the energizing circuits for the actuating coils 83_a to 83₇, the collector rings 77_a to 77₇ which are connected to one side of such coils are connected by a series of conductors 85_a to 85₇ arranged within the extension shaft 76 to a plurality of disc-shaped distributors 86, 87 and 88 which are secured in spaced relation on such shaft between its two ends. As illustrated best in Figs. 7 to 12, inclusive, these distributors each comprises a series of twelve arc-like conductor segments 91_a to 91₇ which are mounted on the outer edge of each distributor in insulated relation to each other, and connected in parallel relation by conductors 90_a to 90₇ to the conductors 85_a to 85₇, respectively, which are connected between the distributors and the collector rings 77_a to 77₇.

Adjacent the distributors 86, 87 and 88 there is mounted a series of gears 92, 93 and 94. This series is meshed with a second series of gears 95, 96 and 97, respectively, mounted on a series of relatively short shafts 98, 99 and 101 mounted in suitable bearing stands 102, 103 and 104. On these latter shafts there is loosely mounted a series of brush carriers 105, 106 and 107 which are each equipped with a pair of diametrically opposed brushes 109_a and 109_b, 111_a and 111_b, and 112_a and 112_b, arranged to contact the conductor segments 91_a to 91₇ on the distributors 86, 87 and 88, respectively, when they are rotated there-over. To energize these brushes they are connected to collector rings 113, 114 and 115 mounted on the brush carriers 105, 106 and 107, respectively, which are contacted by brushes 116, 117 and 118, respectively, mounted in the bearing stands 102, 103 and 104. These in turn are connected by conductors 119, 121 and 122 to an extension M₂ of line conductor L₁. Hence when the extensions M₁ and M₂ of line conductors L₁ and L₂ are energized, a circuit is established through one of the relay actuating coils 83 each time one of the brushes on one of the brush carriers is moved into contact with one of the conductor segments on the associated distributor.

For operating the brush carriers 105, 106 and 107, a series of ratchet wheels 126, 127 and 128 is mounted on and keyed to the brush carrier shafts 98, 99 and 101, respectively, adjacent such carriers. Cooperating with these, as best shown

in Figs. 7 and 11, is a series of dogs 129, 131 and 132 which are pivotally mounted on the brush carriers 105, 106 and 107 in a manner to engage the teeth of the ratchet wheels, springs 133 being connected between each of them and the brush carriers to normally bias them into engagement with the teeth of the associated ratchet wheels.

To disengage the dogs 129, 131 and 132 from the ratchet wheels and also hold the brush carriers in a preselected position when not in operation, a series of latches 134, 135 and 136 is mounted adjacent the brush carriers to engage a notch 130 in each of the brush carriers and the end of a tailpiece 137 provided on each dog. To insure the carriers being stopped by the latches when the latter engage the tailpieces, a lug 138 is provided on each brush carrier to engage the tailpieces 137 after the latches have moved them sufficiently to disengage the dogs from the teeth of the ratchet wheels. These latches 134, 135 and 136 are normally held in a position to engage the tailpieces 137 by suitable means, such as a spring, not illustrated, and are equipped with electromagnet coils 139, 141 and 142 for moving them to an unlatched position. To energize these coils they are connected to the extensions M₁, M₂ of the line conductors L₁, L₂ by conductors 143, 144 and 145 in which manually operable switches 146, 147, and 148, respectively, are provided for selecting which of the brush carriers will be set in operation.

It is the purpose of the brush carrier and distributor units to provide for automatically and selectively controlling the operation of the pins 56 on the pin wheel 54 to determine the lengths of the cuts which the shear will produce. To attain this end the brush carriers and distributors are so designed that the brushes contact only one conductor segment on a distributor each time a brush is rotated over the distributors, and to contact subsequent segments at regular intervals as long as the brush carriers are rotated. To effect such operation, the gears 92 and 95, 93 and 96, and 94 and 97 mounted on the control drive shaft extension 76 and the brush-supporting shafts 98, 99 and 101, respectively, are designed with a ratio which will provide the sequence of operations required. In the present apparatus the ratios of these gears are 12 to 8, 12 to 10, and 12 to 12, and the brush carriers are so proportioned that when they are rotated the brushes 109_a and 109_b on carrier 105 strike every fourth conductor segment on the distributor 86, the brushes 111_a and 111_b on carrier 106 every fifth segment on the distributor 87, and the brushes 112_a and 112_b every sixth segment on the distributor 88. Hence, if brush carrier 105 is placed in operation, it will cause every fourth pin 56 on the pin wheel 54 to produce a cut which will result in a cut being made on every one and one-third revolutions of the blade carriers 6 and 7. When carrier 106 is operated a cut will be produced by every fifth pin 56 or on every one and two-thirds revolutions of the blade carriers, and when carrier 107 is operated a cut will be produced by every sixth pin 56 or on every two revolutions of the blade carriers.

As is obvious, the number and ratio of the brush carriers and distributor units may be increased to increase or alter the range of lengths which the shear can be caused to produce.

In order to insure the brushes on the brush carriers striking the conductor segments on the distributors in the proper manner so that they

will engage only one segment each time they pass over the distributor, the teeth on the ratchet wheels 126, 127 and 128 are correlated with the conductor segments on the associated distributors 86, 87 and 88. For example, ratchet wheel 126 is provided with eight teeth, ratchet wheel 127 with ten teeth, and ratchet wheel 128 with twelve teeth, and these are so timed with the distributors that when the dogs 129, 131 and 132 engage them they cause the associated brushes to be brought into engagement with the distributor segments at the proper time. In addition, the latches 134, 135 and 136, as indicated in Figs. 11 and 12, are so located that the brushes on the associated brush carriers are held, when not in use, in such a position that they will strike the first conductor segment which passes under the brush carriers after the latches are released.

To eliminate waste on the first cut which the shear makes on a piece of stock fed into it, a flag switch 149 is adjustably mounted in the path of the stock 151 to be engaged by the leading end thereof as it approaches the shear which is designated at S in Fig. 7. Such flag switch, as illustrated, is connected to a switch 152 which is adapted to connect line conductors L₁ and L₂ to the extensions M₁ and M₂ when the flag is closed. Hence when one of the switches 146, 147 or 148 is closed and the latch 134, 135 or 136 associated therewith is thereby rendered operable, the brush carrier controlled by the operated latch will be set in motion as soon as the extensions M₁ and M₂ are energized by the closing of the flag switch. Consequently, by positioning the flag switch properly with respect to the movement of the distributors and the blade carriers, the shear can be made to produce first cuts which will vary in length an amount of not more than one-third of a revolution of the blade carrier, which is the maximum distance the carriers may travel during the time it takes the ratchet wheels to travel the length of one of the ratchet wheel teeth.

By way of illustrating the operation of the invention, assume that the manually operable switch 148 is closed, and the latch magnet 142 operated to put brush carrier 107 in service to produce cuts on every two revolutions of the blade carriers as hereinbefore described. Also, assume that the lower blade carrier 7 is in its normal inactive position at the lower end of its reciprocating stroke, and that a piece of stock 151 is being fed into the shear at a lineal speed equal to the peripheral speed of the blade carriers. When the front end of the stock 151 strikes the flag switch 149 mounted in front of the shear such switch will be closed, and it in turn will close the switch 152. Thus, the normally deenergized extensions M₁, M₂ of line conductors L₁, L₂ will be energized. As soon as these are energized, due to switch 148 being closed, latch 136 will be actuated and dog 132 released. This in turn connects brush carrier 107 to its driven supporting shaft 101. With the engagement of dog 132 in the ratchet wheel 128, brush 112a will be moved into contact with one of the conductor segments on the distributor 88, which assume will be segment 91a. When such contact is made a circuit will be established which is traced from the extension M₂ of line conductor L₁ through conductor 122, brush 118, collector ring 115, brush 112a on brush carrier 107, conductor segment 91a of distributor 88, conductor 90a, conductor 85a, collector ring 77a on shaft 76, conductor 84a, coil 83a of relay 74a, conductor 82a, conductor band 79a on drum switch 78, and

conductor 81 to the extension M₁ of line conductor L₁. With the energization of such circuit, relay 74a closes, and in closing completes a circuit which is traced from line conductor L₁ through conductor 73, the common collector ring 69 on the pin wheel supporting shaft 55, conductor 71, coil 67a mounted on pin 56a, conductor 71a, collector ring 69a, conductor 72a, and the bridging member 75a of relay 74a to line conductor L₂. With the completion of this circuit, pin 56a is actuated to engage the Geneva wheel, which it does as soon as it is rotated into engagement with one of the slots 65.

In order to maintain the magnet 67a on pin 56a energized after the brush 112a on brush carrier 107 passes out of engagement with the conductor segment 91a of the associated distributor 88, which it does before the pin has time to turn the Geneva wheel the required amount for each cut, a holding circuit is provided for the actuating coil 83a of relay 74a. This holding circuit is formed by a bridging member 153a which is mounted on the relay 74a with its associated contacts connected to the distributor side of the coil 83a and to line conductor L₂, respectively. Holding circuits of this character are provided by bridging members 153a to 153i on all of the relays 74a to 74l. As soon as such bridging member 153a is closed the circuit for the actuating coil 83a of relay 74a is traced from line conductor L₂ through the drum switch 78 as before to line conductor extension M₁, and such latter circuit is maintained until the pin 56a passes out of engagement with the Geneva wheel, at which time the interruption in the conductor band 79a of switch 78 is timed to pass under the brush on such switch connected to conductor 82a and break the circuit. When such circuit is broken the spring 63 on the pin 56a returns the pin to its inoperative position in readiness for its next operation. A similar arrangement is of course carried out in all of the interrupted conductor bands 79a to 79l on the drum switch, so that each pin 56 used to produce a cut is automatically rendered inoperative as soon as it passes from engagement with the Geneva wheel. To insure the pins 56 being returned to their inoperative position in case the springs 63 fail to function a cam 80 is provided in the casing 100 in which the Geneva and pin wheels are housed and disposed to engage such pins as the pin wheel is rotated over it.

When brush 112b engages the distributor 88 a similar cycle of operation is inaugurated differing only in that segment 91b controls the circuits established, and brings pin 56b into service. As long as the brush carrier 107 is rotated, these circuits are automatically repeated and the carrier 107 is continued in operation until the piece of stock is completely passed through the shear.

When the tail end of the piece of stock passes from under the flag switch 149, such switch falls open, and in doing so causes the line switch 152 to open. The latter in opening deenergizes the latch magnet 142 which allows the latch to return to its normal dog-engaging position where it picks up the tail-piece of the dog 132 and stops the brush carrier in a position ready for starting when the next piece of stock is fed into the shear. To insure against any possibility of the shear missing the last regular cut, switch 152 is provided with a time delay which holds it closed sufficiently to attain such end after the strip 150 passes out of contact with the flag switch 149. The operation, of course, is the same when the other brush carriers are operated, except

that every fifth and fourth pin 56 is brought into service by them to produce cuts of one and two-thirds, and one and one-third revolutions of the blade carriers, respectively.

- 5 To produce cuts intermediate the length which the shear will make when operated at the same speed as the stock, as is contemplated in the foregoing description, the gear change unit 32 is brought into service. For such operation, a 10 brush carrier is selected for service which under normal operation causes cuts to be produced which are the nearest longer length to those desired. The gear change unit 32 is then adjusted to speed up the operation of the shear 15 sufficiently to produce the exact length of cuts desired. As will be readily appreciated, because of the plurality of blades on the blade carriers, and the fact that they may be used selectively, it is unnecessary for this purpose to vary the speed 20 of the shear from that of the stock sufficiently to in any way interfere with the operation of the shear.

As referred to hereinbefore, any number of brush-carrier pin-selecting units may be used 25 to render the shear capable of producing cuts of any practical length desired. This will be appreciated when it is considered that if one of the brushes from each of the carriers 105, 106 and 107 is removed, such carriers will produce cuts of 30 twice the length they do when the two brushes are used as described above. As also previously mentioned the lengths of the cuts may be varied by varying the speed of the pin wheel 54 with 35 respect to the speed of the blade carriers. For example, as stated hereinbefore, if the pin wheel 54 is operated at half the speed of the blade carriers every other blade may be caused to produce a cut as a minimum length, and by increasing the ratio of such drive the minimum length may 40 be correspondingly increased. Further, a greater or lesser number of blades may be used on the blade carriers with the proper corresponding changes in the number of lobes 24 on the cam wheels 21 and pins 56 on the pin wheel, although 45 the arrangement illustrated here is recommended as the most practical design for most purposes and general use.

According to the provisions of the patent statutes, I have explained the principle and mode 50 of operation of my invention, and have illustrated and described what I now consider to be its best embodiment. However, I desire to have it understood that, within the scope of the appended claims, the invention may be practiced 55 otherwise than as specifically illustrated and described.

I claim:

1. In a flying shear, a movably mounted rotary 60 blade carrier equipped with a plurality of equally spaced cutting blades, means for moving said carrier into and out of cutting position, a Geneva wheel for operating said carrier-moving means, and means for selectively operating said Geneva wheel.

65 2. In a flying shear, a movably mounted rotary blade carrier equipped with a plurality of equally spaced cutting blades, means for moving said carrier into and out of cutting position, a Geneva wheel for operating said carrier-moving means, 70 means driven in synchronism with said blade carrier for actuating said Geneva wheel, and means for selectively controlling the connection of said Geneva wheel actuating means to said Geneva wheel.

75 3. A flying shear comprising a pair of rotary

blade carriers equipped with an equal plurality of uniformly spaced cutting blades, means for moving one of said carriers into and out of cutting relation with the other, means driven in timed relation with the blades on said blade carriers for selectively moving said adjustable carrier into and out of cutting relation with the other carrier at an instant when the blades thereon are moved in cutting opposition to produce a cut, and means set in motion by the stock fed to the 10 shear for automatically controlling said selectively operable carrier adjusting means.

4. A flying shear comprising a pair of rotary 15 blade carriers equipped with an equal plurality of uniformly spaced cutting blades, means adjustably supporting one of said carriers out of cutting relation with the other, means for driving said carriers in positive synchronism, means for moving said adjustably supported carrier into and out of cutting relation with the other in such 20 a manner that only one pair of cooperating blades on the two carriers moves into cutting opposition while the carriers are together, and means for selectively controlling said carrier-adjusting mechanism to utilize the cutting blades at random in controlling the lengths of the cuts.

25 5. A flying shear comprising a pair of rotary blade carriers equipped with an equal plurality of uniformly spaced cutting blades, means normally supporting one of said carriers out of cutting relation with the other, means for moving said normally separated carrier into cutting relation with the other carrier, means for continuously driving said carriers in positive synchronism and other means rendered operable when the 30 carriers are moved together for positively preventing said cutting blades interfering with each other and also holding them in proper cutting relation.

35 6. A flying shear comprising a pair of rotary 40 blade carriers equipped with an equal plurality of uniformly spaced cutting blades, means adjustably supporting one of said carriers out of cutting relation with the other, means for driving said carriers continuously in positive synchronism, selectively operable means driven in synchronism with said carriers for moving said 45 adjustably supported carrier into and out of cutting relation with the other in timed relation with the moving of the cutting blades on the two carriers into cutting opposition, and means for effecting intermittent operation of said selectively operable carrier-moving means to determine the lengths of the cuts.

50 7. A flying shear comprising a pair of rotary 55 blade carriers equipped with an equal plurality of uniformly spaced cutting blades, means adjustably supporting one of said carriers out of cutting relation with the other, means for driving said carriers continuously in positive synchronism, selectively operable means driven in synchronism with said carriers for moving said adjustably supported carrier into and out of cutting relation with the other in timed relation with the moving 60 of the cutting blades on the two carriers into cutting opposition, means for effecting intermittent operation of said selectively operable carrier moving means to determine the lengths of the cuts, and means for varying the operation of said last-mentioned means to vary the lengths of the cuts.

65 8. A flying shear comprising a pair of rotary 70 blade carriers equipped with an equal plurality of uniformly spaced cutting blades, means adjustably supporting one of said carriers out of

cutting relation with the other, means for driving said carriers continuously in positive synchronism, selectively operable means driven in synchronism with said carriers for moving said 5 adjustably supported carrier into and out of cutting relation in timed relation with the moving of the cutting blades on the two carriers into cutting opposition, means for effecting intermittent operation of said selectively operable carrier-moving means to determine the lengths of 10 the cuts, and means responsive to the stock fed into the shear for setting said last-mentioned means in operation.

9. A flying shear comprising a pair of rotary 15 blade carriers each equipped with a plurality of uniformly spaced cutting blades, means adjustably supporting one of said carriers out of cutting relation with the others, means driven in synchronism with said carriers for selectively moving 20 said adjustably supported carrier into and out of cutting relation with the other carrier in a manner to utilize at random the different blades on said carriers to control the lengths of the 25 cuts, and means for varying the operation of said selective operable carrier-moving means to vary the lengths of the cuts.

10. In combination, a rotary flying shear comprising a pair of rotatably mounted blade carriers, equipped with a plurality of cutting blades, 30 means for moving one of said carriers into and out of cutting relation with the other in timed relation with the blades thereon for varying the lengths of the cuts, means for feeding stock into the shear, means for synchronously driving both 35 said shear and stock-feeding means, means for selectively moving one of said shear carriers into and out of cutting relation with the other to produce cuts, and means for varying the ratios of speed between said stockfeeding means and 40 said shear to vary the lengths of the cuts.

11. In a flying shear, a laterally adjustable rotary blade carrier equipped with a cutting blade, means adapted to normally support said carrier in an inoperative position, means for 45 moving said support to move said carrier into cutting position, and means actuated with said carrier for preventing the blades on said carrier contacting the stock being severed between cuts.

12. A flying shear comprising a pair of rotary 50 blade carriers equipped with cutting blades, means for normally supporting one of said carriers out of cutting relation with the other, means for actuating said carrier support to place the carrier supported thereby in position to produce 55 cuts, a Geneva wheel for actuating said carrier support, means driven in synchronism with said carriers for selectively controlling the operation of said Geneva wheel, and a common source of power for driving said shear, said Geneva wheel, 60 and said Geneva wheel operating control means.

13. In a flying shear, a pair of rotary blade carriers, means for moving one of said carriers into and out of cutting relation with the other, means for controlling the operation of said carrier-adjusting means comprising a rotatably mounted distributor, a plurality of contiguous conduction segments mounted in electrically insulated relation on said distributor, a series of electrical circuits connected to said segments 65 and to means comprising said carrier-adjusting means, a rotary brush carrier mounted for rotation in a plane parallel with and adjacent to said distributor, a brush mounted on said carrier to engage said segments when said brush carrier is moved over said distributor, and means 70

for supplying current to said brush for energizing said distributor segments and the circuits connected thereto.

14. In a flying shear, a pair of rotary blade carriers, means for moving one of said carriers into and out of cutting relation with the other, means for controlling the operation of said carrier-adjusting means comprising a plurality of rotatably mounted distributors, a plurality of contiguous conductor segments mounted in electrically insulated relation on each of said distributors, a rotary brush carrier mounted for rotation in a plane parallel with and adjacent to each of said distributors, a brush mounted on each of said brush carriers to contact the conductor segments on the adjacent distributors when the brushes are rotated thereover, means for driving each of said carriers at a different relative but synchronized speed with said distributors, a plurality of circuits connected in parallel to the segments of said distributors and to said carrier-adjusting means, and means for selectively energizing said brush carriers. 15 20 25

15. In combination with a flying shear, a control system for controlling the operation of the shear comprising a disc-shaped distributor equipped with a plurality of conductor segments mounted on one face of said distributor disc adjacent the outer edge thereof, a brush carrier mounted for rotation in a plane parallel with and adjacent to said distributor, with a portion of it overlapping said distributor, a brush mounted on said carrier to contact the conductor segments on said distributor at regular intervals as it is rotated thereover, means for selectively energizing said brush, means for driving said carrier in timed relation with said distributor disc so that only one of said conductor segments is contacted by said brush each time the brush is moved over the distributor, and a plurality of 30 35 40 shear-operating circuits connected to said conductor segments.

16. In a flying shear, a pair of rotary blade carriers equipped with cutting blades, means including a radially slotted wheel for moving one of said carriers into and out of cutting relation with the other carrier, a pin wheel equipped with a plurality of pins for operating said slotted wheel, means for selectively operating said pins to engage said slotted wheel, means for resiliently returning said pins to their inoperative position after each operation thereof, and cam means for positively-returning said pins to their inoperative position in case said resilient means fails to work. 45 50 55

17. In a flying shear, a pair of rotary blade carriers equipped with cutting blades, a cam for moving one of said carriers into and out of cutting relation with the other in timed relation with the movement of said blades, a slotted wheel for actuating said cam means, a pin wheel equipped with a plurality of adjustable pins for operating said slotted wheel, and means for holding said slotted wheel in a position to receive the pins in said pin wheel when not being moved by such pins. 60 65

18. A flying shear comprising a pair of rotary blade carriers each equipped with a plurality of uniformly spaced cutting blades, means adjustably supporting one of said carriers out of cutting relation with the other, means for driving both of said carriers in positive synchronism, means for moving said adjustable carrier to selectively utilize the cutting blades thereon for producing cuts, and means responsive to the ap- 70 75

proach of a piece of stock fed to the shear for controlling the carrier-adjusting means in such a way as to produce a first or cropping cut of length not greater than the distance between 5 the blades on the carriers.

19. In a flying shear, a movably mounted rotary blade carrier equipped with a plurality of equally spaced axially disposed cutting blades, cam means for moving said carrier into and out of cutting 10 position, a Geneva wheel disposed to intermittently operate said cam means, and means driven in synchronism with said carrier for operating said Geneva wheel in timed relation with the cutting blades on the carrier.
- 15 20. In a flying shear, a rotary blade carrier equipped with a plurality of uniformly spaced axially disposed cutting blades, a cam wheel equipped with a plurality of equally spaced cam lobes adapted to normally support said carrier 20 in a non-operative position and to move it into and out of cutting position each time it is rotated an angular distance equal to the length of one of said lobes, and means driven in synchronism with said carrier for intermittently operating said 25 cam wheel in timed relation with the blades in said carrier.

21. In a flying shear, a pair of rotatably mounted blade carriers each equipped with a plurality of equally spaced axially disposed cutting blades, 30 means rigidly holding one of said carriers against other than rotary movement, means comprising a rotatably mounted cam disposed to normally support said other carrier in spaced non-operative relation with said rigidly supported carrier 35 and adapted when rotated to move it into cutting relation therewith, and means for so operating said cam as to selectively utilize the blades on said carriers to control the lengths of the cuts.

22. In a flying shear, a pair of rotatably mounted blade carriers each equipped with a plurality of equally spaced axially disposed cutting blades, 40 means rigidly holding one of said carriers against other than rotary movement, means comprising a rotatably mounted cam disposed to normally support said other carrier in spaced non-operative relation with respect to said rigidly supported carrier and adapted when rotated to move the carrier supported by it into cutting relation with the other, and means for operating said 45 cam in timed relation with said carriers to selectively utilize the different blades on the carriers and thereby control the lengths of the cuts.

23. In a flying shear, a pair of rotatably mounted blade carriers each equipped with a plurality of equally spaced axially disposed cutting blades, 55 means rigidly holding one of said carriers against other than rotary movement, means for moving said other carrier into and out of cutting relation with said rigidly supported carrier, said means comprising a rotatably mounted cam mechanism designed to normally support said movable carrier in spaced non-operative cutting relation with the rigidly supported carrier and adapted when rotated to move the carrier supported thereby 60 into cutting relation with the other carrier, and means synchronized with said carriers for intermittently operating said cam and adapted to move said movable carrier into and out of cutting relation with said rigidly supported carrier 65 each time it is actuated and in such a way that only one cut is produced with each such operation.

24. In a flying shear, a pair of rotatably mounted blade carriers each equipped with a plurality of equally spaced axially disposed cutting blades, 70

means for driving said carriers in positive synchronism and in such timed relation that the blades of one will move into cutting opposition with those of the other with each revolution thereof, means comprising a rotatably mounted cam adapted to normally support at least one of said carriers in spaced non-operative relation with the other and when rotated to move the carrier supported thereby into cutting relation with the other, and means driven in synchronism 10 with said carriers for operating said cam to selectively utilize the blades on said carriers and control the lengths of the cuts.

25. A flying shear comprising a supporting frame, a pair of rotary blade carriers equipped with an equal plurality of uniformly spaced axially disposed cutting blades mounted in said frame, means for rigidly supporting one of said carriers against other than rotary movement, cam means adapted to normally support the other carrier 15 out of cutting relation with said rigidly supported carrier and to move it into and out of cutting relation therewith when operated, means connected to a Geneva wheel for intermittently operating said cam means, and means driven in synchronism 20 with said carriers for operating said Geneva wheel.

26. A flying shear comprising a supporting frame, a pair of rotary blade carriers equipped with an equal plurality of uniformly spaced axially disposed cutting blades mounted in said frame, means for rigidly supporting one of said carriers against other than rotary movement, cam means adapted to normally support the other carrier out of cutting relation with said rigidly supported carrier 30 and adapted when rotated to move it into cutting relation with said rigidly supported carrier, means constantly urging said latter carrier toward said cam means, a Geneva wheel for intermittently operating said cam means, and means for intermittently operating said Geneva wheel to move the carrier 35 supported by said cam means into and out of cutting relation with said rigidly supported carrier in timed relation with said cutting blades.

27. A flying shear comprising a supporting frame, a pair of rotary blade carriers equipped with an equal plurality of uniformly spaced axially disposed cutting blades mounted in said frame, means for driving said carriers in positive synchronism and in such timed relation that the blades on each carrier move into cutting opposition with cooperating blades on the other with each revolution thereof, cam means adapted to normally support at least one of said carriers out of cutting relation with the other and to intermittently move each carrier into and out of cutting opposition with the other when operated, a Geneva wheel connected to said cam means for intermittently moving the carrier actuated thereby into and out of cutting relation with the other carrier, and means driven in synchronism with 50 said carriers for operating said Geneva wheel.

28. In a flying shear, a pair of rotary blade carriers equipped with an equal plurality of uniformly spaced axially disposed cooperating cutting blades, a cam adapted to normally support at least one of said carriers out of cutting relation with the other and to move the carrier supported thereby into and out of cutting opposition with the other when actuated, a Geneva wheel connected to said cam, and means driven 65 in synchronism with said carriers for operating said Geneva wheel, said means being adapted to produce a sufficient movement of said cam each time it actuates said Geneva wheel to move the carrier supported thereby into and out of cutting 70

relation with the other carrier and to do so in timed relation with said cutting blades.

29. In a flying shear, a movably mounted rotary blade carrier equipped with a plurality of 5 equally spaced axially disposed cutting blades, cam means disposed to normally support said carrier in a non-operative position and when operated to move the carrier into and back out of cutting position, a Geneva wheel coupled to 10 said cam, a pin wheel equipped with a plurality of selectively operable pins operably associated with said Geneva wheel in such a way that when the pin wheel is rotated and one of said pins is actuated to engage the Geneva wheel it will move 15 the latter sufficiently to cause the blade carrier to be moved into and out of cutting position during the period the pin is engaged in the Geneva wheel, and means for driving said pin wheel in synchronism with said carrier.
- 20 30. In a flying shear, a movably mounted rotary blade carrier equipped with a plurality of equally spaced axially disposed cutting blades, cam means disposed to normally support said carrier in a non-operative position and when 25 operated to move the carrier into and back out of cutting position, a Geneva wheel coupled to said cam, a pin wheel equipped with a plurality of selectively operable pins operably associated with said Geneva wheel in such a way that when 30 the pin wheel is rotated and one of said pins is actuated to engage the Geneva wheel it will move the latter sufficiently to cause the blade carrier to be moved into and out of cutting position during the period the pin is engaged in the 35 Geneva wheel, means for driving said pin wheel in synchronism with said carrier, and means for selectively controlling the actuation of said pins to control the lengths of cuts produced by the shear.
- 40 31. In a flying shear, a rotary blade carrier equipped with a plurality of equally spaced axially disposed cutting blades mounted in a pair of vertically adjustable end bearings, a pair of cam wheels disposed to reciprocate said bearings 45 mounted on a shaft arranged below said carrier, a series of equally spaced lobes formed on the periphery of said cams and adapted when the cams are actuated to move said carrier into and out of cutting position, a Geneva wheel mounted 50 on said cam shaft, a pin wheel equipped with a plurality of adjustable pins for actuating said Geneva wheel operably associated therewith, said pins being adapted to be engaged in the slots of the Geneva wheel when the pin wheel is rotated 55 and to turn the latter wheel an amount sufficient to move the carrier into and out of cutting position during the period they are engaged in such slots, and means for driving said pin wheel in timed relation with said carrier.
- 60 32. A flying shear comprising a supporting frame, a pair of rotary blade carriers equipped with an equal plurality of uniformly spaced axially disposed cutting blades rotatably mounted in said frame, means for so driving said carriers that each blade on each carrier moves into cutting opposition with a cooperating blade on the other carrier each time the carriers are rotated, cam means adapted to normally support one of said carriers sufficiently out of contact with the other to allow a piece of stock to be passed between the two without interference therewith and to move such carrier into and out of cutting relation with the other carrier when rotated, a Geneva wheel coupled to said cam, a pin wheel 70 for operating said Geneva wheel driven in syn-

chronism with said carriers, a plurality of pins movably mounted in said pin wheel for engagement with said Geneva wheel, said pins being adapted to move said Geneva wheel an amount sufficient to cause said cam means to move the carrier actuated thereby into and out of cutting relation with the other carrier during the period they are engaged in such wheel, and means for selectively operating said pins to determine the lengths of the cuts.

5 33. A flying shear comprising a supporting frame, a pair of rotary blade carriers equipped with three equally spaced axially disposed cutting blades rotatably mounted in said carriers, means for so driving said carriers that the blades on the two move into cutting opposition with each other each time the carriers are rotated, a cam wheel provided with six equally spaced lobes on the periphery adapted to normally support one of said carriers sufficiently out of contact with the other to permit a piece of stock being passed between the two without interference therewith and to move the carrier supported thereby into and out of cutting relation with the other carrier each time it is rotated the length 20 of one of said lobes, a Geneva wheel provided with a series of slots spaced 30° from said cam lobes coupled to said cam, a pin wheel driven in synchronism with said carriers and equipped with twelve movable pins so mounted with respect to 30 said Geneva wheel that they may each be utilized to move said Geneva wheel a distance equal to the length of one of said cam lobes, and means for selectively operating said pins.

35 34. A flying shear comprising a supporting frame, a pair of blade carriers equipped with an equal plurality of uniformly spaced axially disposed cutting blades rotatably mounted in said carriers, means for positively driving said carriers to bring the blades of the two into cutting 40 opposition with each other each time the carriers are rotated, cam means adapted to normally support one of said carriers sufficiently out of contact with the other to permit a piece of stock to be passed between the two without interference therewith and to move the carrier supported thereby into and out of cutting relation with the other carrier when rotated a given angular distance, a Geneva wheel coupled to said cam, a pin wheel equipped with a plurality of movable pins for operating said Geneva wheel being adapted to move said cam means sufficiently to move the carrier operated thereby into and out of cutting relation with the other carrier each time it is actuated by one of said pins, means for driving said pin wheel in synchronism with said carriers, means for operating said pins, and means driven in synchronism with said pin wheel for selectively controlling said pin-operating means.

45 50 55 60

35. In a flying shear, a rotary blade carrier equipped with a plurality of equally spaced cutting blades, a cam wheel equipped with a plurality of cam lobes arranged to normally support said carrier in a non-operative position and to move it into and out of cutting position each time said wheel is rotated the distance of one of said lobes, a Geneva wheel coupled to said cam wheel, a pin wheel driven in synchronism with said carrier, a plurality of movable pins mounted in said pin wheel, means for moving said pins to engage said Geneva wheel, said pins being adapted to move the Geneva wheel a distance equal to the length of one of said cam lobes during the period of their engagement therein, means for selectively operat-

ing said pins to determine the lengths of the cuts, and means actuated by a piece of stock being fed into the sheer for setting said pin-selecting means in operation.

- 5 36. In a flying shear, a rotary blade carrier equipped with a plurality of equally spaced axially disposed cutting blades, means for driving said carrier continuously, a cam wheel adapted to normally support said carrier in an inoperative position and to move it into and out of cutting position when rotated, means driven in synchronism with said blade carrier for intermittently operating said cam wheel in timed relation with said blades, and means actuated with said carrier for preventing the blades on said carrier contacting the stock being severed before and after each cut.

37. In a flying shear, a blade carrier equipped with a plurality of equally spaced cutting blades mounted for both rotary and reciprocatory movement, a cam wheel provided with a series of cam lobes arranged to reciprocate said carrier into and out of cutting position as it is rotated but adapted to normally support the carrier in an inoperative position, a Geneva wheel connected to said cam, a pin wheel equipped with a plurality of normally idle adjustable pins disposed when actuated to do so to engage said Geneva wheel and to rotate it a distance equal to one of said cam lobes during the period it engages the Geneva wheel, means for driving the pin in synchronism with the blade carrier, a series of electromagnets for operating said pins, a series of distributors for actuating said magnets, and a series of control brushes driven in synchronism with said distributor and arranged to selectively control the operation of said pin magnets.

38. In combination with a Geneva wheel, a driven pin carrier equipped with a plurality of pins for engaging and rotating said Geneva wheel, means normally holding said pins in an inoperative position, and means for individually actuating them to engage the Geneva wheel.

39. In combination, a Geneva wheel, a driven pin carrier equipped with a plurality of pins for engaging and rotating said Geneva wheel, resilient means for normally holding said pins in an inoperative position, and electromagnet means for individually actuating them to their operative position.

50 40. In combination, a Geneva wheel, a driven pin carrier equipped with a plurality of pins for engaging and rotating said Geneva wheel, means

normally holding said pins in an inoperative position, means for individually operating them to engage the Geneva wheel, and means for preventing the pins jamming in the event they do not register with the slots in the Geneva wheel when they are rotated into engagement with it.

5

41. In combination, a Geneva wheel, a driven pin wheel equipped with a plurality of adjustable pins operably associated with said Geneva wheel, means for individually adjusting said pins to engage said Geneva wheel, and means for selectively controlling the operation of said pin-adjusting means.

42. In a flying shear, a movably mounted rotary blade carrier equipped with a cutting blade, means for moving said carrier into and out of cutting position, and a Geneva wheel for operating said carrier-moving means.

43. In a flying shear, a cutting element comprising a rotary blade carrier equipped with a plurality of equally spaced cutting blades, a second cutting element adapted to cooperate with said first-mentioned element in the making of cuts, means for moving one of said elements into and out of cutting position with the other, a Geneva wheel for operating said last-mentioned means, and means for selectively operating said Geneva wheel.

44. A flying shear comprising a cutting element equipped with a plurality of uniformly spaced cutting blades, a second cutting element arranged to cooperate with said first-mentioned cutting element in the production of cuts, means for adjustably supporting one of said cutting elements out of cutting relation with the other, means for driving said cutting elements, selectively operable means driven in synchronism with said cutting blades for moving said adjustable cutting element into and out of cutting relation with the other in timed relation with the moving of said cutting blades into cutting position, and means for effecting intermittent operation of said selectively operable cutting element moving means to determine the length of the cuts.

45. In a flying shear, a pair of cooperating cutting elements, means for moving one of said cutting elements into and out of operative cutting relation with the other, and a Geneva wheel for operating said cutting element moving means.
